UNITED STATES PATENT OFFICE.

TANDY W. TONEY, OF EUFAULA, ALABAMA.

CONDENSER.

No. 836,618.

Specification of Letters Patent.

Patented Nov. 20, 1906.

Application filed August 19, 1905. Serial No. 274,889.

To all whom it may concern:

Be it known that I, TANDY W. TONEY, a citizen of the United States, residing at Eu-
5 faula, in the county of Barbour and State of Alabama, have invented new and useful Im-
provements in Condensers, of which the fol-
lowing is a specification.

This invention relates to condensers.

The invention may be used with various
10 kinds of steam-engines.

By virtue of my invention I liquidize the exhaust-steam from an engine and resupply the liquid to the boiler of said engine. In the present case the liquidization of the ex-
15 haust-steam is secured by water, the water being heated by the exhaust-steam, by rea-
son of which there is an equalization of tem-
perature of the two constituents. The re-
sultant mixture, composed of liquidized
20 steam and water heated by the steam, is sup-
plied to the boiler of the engine, whereby economy is assured, for, as will be apparent, I liquidize the exhaust-steam and return it after liquidization to the boiler.

25 By the invention I can save large quantities of fuel and water.

From what has been stated it will be evi-
dent that the device is for the liquidizing of
30 exhaust-steam and returning it to a boiler,
as hereinafter explained.

In the drawings forming a part of this specification I illustrate a simple form of em-
bodyment of my invention, which to enable
those skilled in the art to practice said inven-
35 tion I will describe in detail in the following description, while the novelty of the inven-
tion will be included in the claims succeeding
said description.

In the said drawings, Figure 1 is a perspec-
40 tive view of the apparatus. Fig. 2 is a lon-
gitudinal sectional elevation of the same.

Like characters refer to like parts through-
out the different views.

In the embodiment of the apparatus illus-
45 trated the same includes a tank, as 2, of any suitable size and material and which is adapt-
ed to contain water to, say, in the neighbor-
hood of about three-fourths of its height.
Associated with the tank 2 is what may con-
50 veniently be considered an exhaust-steam
pipe 3, adapted in practice to be connected
with the exhaust of a steam-engine. (Not
shown.) For this purpose the exhaust-
steam pipe may have at one end a union or
55 coupling, as 4, of some suitable kind. The
apparatus has a number of pipes or conduits

and their equivalents, and these for conven-
ience are made of separable sections, such as
nipples, T's, elbows, and the like. I do not
deem it necessary, however, to go into a de-
60 tails description of these points, although
by making the conduits or pipes and coöper-
ating parts in sections they may be more
readily separated when necessary to take
down the apparatus or set it up. 65

From the exhaust-steam pipe 3 at least one branch pipe extends. As a matter of fact I have shown three of these branch pipes, and as they are the same in construction each will be denoted by the character 5. The branch 70 pipe 5 are substantially of inverted-U form, the outer legs thereof being connected at their lower ends with the steam-exhaust pipe 3, while the inner legs thereof are extended downwardly through the top of the tank and 75 are connected at their lower ends with the pipe system 6. The pipe system 6 includes a circuit-like frame part and a cross-piece uniting the side bars of said frame part. To the end members of the pipe system 6 the termi- 80 nal branch pipes 5 are connected, while the intermediate branch pipe is connected with the cross-piece. The pipe system, made up of the circuit or continuous-like part and the cross-bar uniting the side bars thereof, is per- 85 forated for the emission of steam, which tra-
verses the same, while the inner legs of the inverted-U-shaped branch pipes 5 are per-
forated for a like purpose. The perforations in the branch pipes extend from the bottom 90 for about in the neighborhood of two-thirds of the height of said branch pipes. The pipe system 6 is contiguous to the bottom of the tank 2 and is located within the same, the steam-exhaust pipe 3 being located outside 95 the tank. Exhaust-steam from the engine, therefore, is conducted by the pipe 3 into the branch pipes 5, which in turn convey the ex-
haust-steam into the tank, where such steam can flow through the perforations in the in- 100 ner legs of the branch pipes and also through the perforations in the pipe system 6 and in intimate association with the water in the tank, so that such water will liquidize the steam, and the latter in turn will heat the 105 water, so that there will be an equalization of temperature of the two constituents, the lat-
ter being subsequently supplied to the boiler, as will hereinafter appear.

I will now set forth the means illustrated 110 for supplying the steam-liquidizing water to the tank 2. A water-supply pipe is shown at

7 and as having or terminating in a transverse head 8. From this head 8 the three pipes 9 are shown as extending, one pipe being for each branch pipe 5. The pipes 9 supply water to the pipes 5 above the perforations in the inner legs of the latter, so that I secure initially a liquidization of the steam before the same leaves the branch pipes 5. The steam and the water, therefore, are brought into intimate mixture before the steam leaves the branch pipes, so that there will be a desirable interchanging of temperature between the two. From the head of the water-supply pipe 7 other pipes, as 10, lead, said pipes 10 being extended through the top of the tank. These pipes 10 are for receiving and conveying any steam that may be in the tank 2 and discharging it into the head 8, where it becomes liquidized, passing from said head into the pipes 9 to be discharged with the water therein into the branch pipes 5, and thence into the tank, where the liquidization of the exhaust-steam is completed. Said pipes 10 are provided with check-valves so arranged that the water from the pipes 9 cannot get into the tank 2; but the steam, if there be any in the tank, can readily flow into the pipes 9 by way of the pipes 10 and head 8.

In the pipes 9 between the head 8 and branch pipes 5 are check-valves of some suitable kind, which prevent exhaust-steam passing to the water-pipe 7, although they freely permit the flow of water to the said branch pipes 5. Any suitable check-valves may be employed for this purpose. Pendent from the exhaust-steam pipe 3 is a draw-off cock or valve 11, which may be manipulated to permit the escape of any liquidized steam in said pipe 3. The pipe 7 will be provided in practice with some suitable means for its connection with a main. For this purpose I have represented a union or coupling 12, and between this coupling or union and the head 8 I interpose a cock or valve located, of course, outside the tank and which may be operated to shut off the supply of water, when occasion requires, to the tank 2 and branch pipes 5.

In adjacence to the main tank 2 is an auxiliary tank 13, from which the water to supply the boiler is directly drawn. At this point I deem it expedient to state that I show neither the boiler nor engine associated therewith, as I consider this to be unnecessary to a full understanding of my invention. Extending from the main tank 2 at vertically-separated points are pipes 14 and 15. These pipes receive at their entering ends, which are located within the main tank, any steam that might not be liquidized therein and convey such steam into the auxiliary tank, and to insure the liquidization of any such steam the delivery ends of the said pipes 14 and 15 are situated near the bottom of the auxiliary tank. These delivery ends are immersed in

the water in the auxiliary tank, the level of such water being at such height to assure this result at all times.

The pipe 14 discharges water into the tank 13 as well as steam. Its main object, however, is for discharging water into said tank 13, although it will be evident it can also discharge steam into said tank 13 received from the tank 2.

The feed-water pipe is designated by 16, and it extends from the tank 13 to conduct the water from such tank to the boiler, and such water, from what has been hereinbefore stated, will be in a hot condition. In some instances it is desirable not to conduct hot water to the boiler primarily, to secure which result I connect a cold-water-feed pipe, as 17, to the feed-water pipe 16 between the boiler and the tank 13. This cold-water supply or feed pipe 17 is provided with a valve, as 18, which is normally closed, but which when occasion requires may be opened to direct cold water into the feed-water pipe 16 and bring about the supply of such cold water to the boiler. The pipe 16 has its entering end below the level of the water in the auxiliary tank. For example, the entering or inlet end of the pipe 16 may be situated in the bottom of said auxiliary tank.

Between the junction of the pipes 16 and 17 and the tank 13 there is a stop-cock 19, which is normally open, but which will be closed when it is desired to supply cold water to the boiler. I provide for the supply of cold water to the boiler instead of hot water in case the injector or inspirator of the pump should fail to start with the hot water. The cold-water-feed pipe 17 can be supplied from a tank (not shown) or in any other desirable way. The exhaust-steam, therefore, from the steam-engine, or a considerable percentage of it, can be employed over and over again, for after it is exhausted it is liquidized, and when liquidized is resupplied to the boiler for further use. I provide means whereby water is utilized to liquidize the exhaust, the steam heating the water, so that the liquid-supply to the boiler will be in a hot or desirable condition. The procedure, as will be understood, is continuous. By the apparatus I effect a great saving of water and fuel.

The system of piping, which I have denoted by 6 and which includes in its make-up a circuitous body, assures the circuitous flow of steam below the surface of the water in the tank 2, as thereby I secure a desirable effect.

In the drawings I have shown a pipe, as 3^a, extending from the exhaust-steam pipe 3. The opposite end of this pipe 3^a opens into a jet or injector, as 13^b, forming a part of the pipe 13^a. As shown by dotted lines in Fig. 1, this pipe 13^a extends downward into the auxiliary tank 13, and it is also connected with the water-supply pipe 7 just above the cock therein. The jet or injector as it re-

ceives steam from the pipe 3^a from the main pipe 3 serves to force water from the auxiliary tank 13 into the tank 2, the water entering the pipe 13^a and then the pipe 7, head 8, 5 pipes 9, and finally into pipes 5, from which it flows into the tank 2.

By the arrangement just set forth I secure a continual flow of water into the branch pipes 5 (whenever the engine is operated) for 10 liquidizing the exhaust-steam in said branch pipes and also in the tank 2. The construction described insures an intermixing of the waters and equalization of the temperature of the same in the two tanks 2 and 13 whenever 15 said engine is at work.

Having thus described the invention, what I claim is—

1. The combination of a water-tank, an exhaust-steam pipe extended into the tank 20 and perforated in the latter, a water-pipe opening into the non-perforated portion of the exhaust-steam pipe, a second tank in communication with the first tank to receive liquid from the latter, and a feed-pipe for supplying the liquidized steam from the second 25 tank to a boiler.

2. The combination of a water-tank, an exhaust-steam pipe extended into said tank and perforated in the latter a water-pipe 30 opening into the non-perforated portion of the exhaust-steam pipe, a second tank in communication with the first tank to receive liquid from the latter, a feed-pipe for supplying the liquidized steam from the second 35 tank to a boiler, and a water-feed pipe opening into said last-mentioned pipe, each of the two last-mentioned pipes having a hand-operable valve.

3. The combination of a water-tank, an 40 exhaust-steam pipe having a branch opening into the tank, that part of the branch within the tank being perforated, a water-pipe opening into the non-perforated portion of the branch and having a check-valve, and a 45 steam-conveying pipe leading from the tank and communicating with said water-pipe.

4. The combination of a water-tank, an exhaust-steam pipe having a branch leading 50 into the tank, that part of the branch within the tank being perforated, a perforated system of piping to which the perforated por-

tion of the branch is connected and in said tank, and a water-pipe connected with the non-perforated portion of said branch.

5. The combination of a water-tank, an 55 exhaust-steam pipe having a plurality of substantially inverted-U-shaped branches leading therefrom, the inner legs of the branches extending into the tank and being perforated, a circuit-like system of perforated 60 piping to which the inner legs of said branches are connected, and water-pipes opening into the non-perforated portions of said branches.

6. The combination of a water-tank, an 65 exhaust-steam pipe having branches leading into said tank, the portions of the branches within the tank being perforated, a water-pipe having a transverse head provided with branches connected with the non-perforated 70 portions of the first-mentioned branches, and steam-conveying pipes connected with and leading from the tank.

7. The combination of a water-tank, an 75 exhaust-steam pipe extended into said tank and perforated in the latter, a water-pipe opening into said exhaust-steam pipe above the perforated portion thereof, a second tank in communication with the first tank, a feed-water pipe leading from said second tank, a 80 pipe extended from the second tank to the water-pipe, and a branch extended from the exhaust-steam pipe and connected with that pipe which extends from the said second tank to said water-pipe.

8. The combination of a water-tank, an exhaust-steam pipe extended into said tank and perforated therein, a water-pipe opening into said exhaust-steam pipe above the perforated portion thereof, a second tank, a plurality 90 of pipes connecting the first and second tanks, and a pipe leading from the second tank, for conducting liquidized steam therefrom.

In testimony whereof I have hereunto set 95 my hand in presence of two subscribing witnesses.

TANDY W. TONEY.
